UNITED STATES PATENT OFFICE.

CLYDE E. SCHULZ, OF FORT DODGE, IOWA, ASSIGNOR TO AUTOMOTIVE RADIATOR MACHINE COMPANY, OF FORT DODGE, IOWA, A CORPORATION.

RADIATOR-REPAIR MACHINE.

1,410,410.

Specification of Letters Patent. Patented Mar. 21, 1922.

Application filed January 13, 1920. Serial No. 351,182.

To all whom it may concern:

Be it known that I, CLYDE E. SCHULZ, a citizen of the United States, and resident of Fort Dodge, in the county of Webster and State of Iowa, have invented a certain new and useful Radiator-Repair Machine, of which the following is a specification.

The object of my invention is to provide a 10 radiator repair machine particularly adapted for use with the radiators used on certain types of automobiles, such, for instance, as the Ford.

A further object is to provide such a machine having a frame and a supporting platform mounted thereon, so arranged that a radiator may be supported on the platform for heating and melting the solder on the radiator, which machine is provided with 20 means for quickly and easily removing the fins from the radiator after the solder has been melted.

Still a further object is to provide such a machine having special mechanism for re- 25 placing the fins in proper position.

Still a further object of my invention is to provide in such a machine a radiator support or platform adapted for movement to position for conveniently carrying out 30 the various operations connected with the repair of the radiator.

With these and other objects in view, my invention consists in the construction, arrangement and combination of the various 35 parts of the device, whereby the objects contemplated are attained, as hereinafter more fully set forth, pointed out in my claims, and illustrated in the accompanying drawings, in which:

40 Figure 1 shows a perspective view of a radiator repair machine embodying my invention.

Figure 2 shows a longitudinal sectional view through the machine.

45 Figure 3 shows a rear elevation of the machine.

Figure 4 shows a detail sectional view 50 illustrating a radiator in position on the machine, and with the parts of the machine in position for removing a fin.

Figure 5 shows a radiator in certain position in the machine, with relation to the fin replacing device; and

Figure 6 shows a view similar to Figure 5, with the fin replacing device in another 55 position of its movement.

In the drawings herewith, I have used the reference numeral 10 to indicate generally the spaced base members which form a support for my machine, and are preferably 60 connected by spaced, transversely arranged frame members 11.

At each side of the machine is a pair of upright spaced angle iron frame members 12, connected at their upper ends by a bar 65 13, as illustrated in Figure 1. Near the upper ends of the uprights 12, on the opposite sides of the machine, are brackets 14.

I provide a platform or support 15, preferably comprising a substantially rectangular member having at its opposite sides ears 16 which are pivoted to the respective brackets 14 by means of short shafts or spindles 17. The ears 16 are located nearer one end of the support 15 than the other, 70 as illustrated clearly in Figures 1 and 2. The support or platform 15 has a plurality of rows of projecting lugs or fingers 18, designed to fit between the fins and tubes of a radiator of the type under consideration, 80 for conveniently holding the radiator on the support or platform.

Projecting forwardly from the upright members 12 at opposite sides of the machine are parallel, substantially horizontal frame 85 members 19 connected at their outer ends by a transverse frame member 20. Braces 21 are provided for further strengthening and supporting the frame members 19.

Supported by the respective frame members 19, near the forward outer ends thereof, are yokes 22. Supported by the yokes 22 is a plurality of transversely arranged burner tubes 23, which are supplied with fuel from a supply tube 24.

On the respective frame members 19, near the rearward ends thereof, adjacent to the uprights 12, are brackets 25 on which are centrally pivoted bell crank levers 26. Pivoted to one of the transverse frame members 11 are spaced, forwardly extending frame members or arms 27, which are connected at their forward ends by a foot treadle member 28. The arms or frame members 27 are pivoted between their ends 100 to links 29, which extend upwardly and

are each secured to one of the bell crank levers 26. The other arm of each bell crank lever is pivoted to a forwardly extending arm 30. The forward ends of the arms 30 are connected by a transverse frame member 31, clearly shown in Figure 1.

At the ends of the member 31 are laterally extending pins 32, which overhang the frame members 19 so as to limit the downward swinging movement of the arm 31. On the transverse frame member 31 is a plurality of downwardly extending teeth 33, which are of such size as to project between two fins of a radiator, and also between the tubes of the radiator, for the purpose hereinafter more fully referred to. Connected with the transverse frame member 31 is a forwardly projecting handle 34.

Connected with the links 29 and with some fixed portions of the frame are coil springs 35 which normally tend to hold the links 29 in the upper positions of their movement for thereby holding the bell crank levers in such position as to retain the members 30 and 31 in their positions nearest the upright members 12.

Mounted for vertical sliding movement between the uprights at each side of the machine, and extending upwardly substantially above the upper ends of the members 12, are uprights 36, which may be in the form of channel bars and which are connected at their upper ends by a cross member 37 provided with a plurality of openings 38, which correspond in their relative positions to the relative positions of the tubes in the radiator, so that the tubes at the bottom of the radiator may be projected through the openings 38.

Pivoted to the uprights 36 are downwardly extending links 37^a. Pivoted to suitable brackets 38 near the lower portions of the frame members 12 at points forwardly of the frame members 12, are arms or frame members 39 which extend rearwardly in the machine, as illustrated in Figures 1 and 2 and 3, and are connected at their rear ends by a transverse treadle member 40, best illustrated, perhaps, in Figures 1 and 2. Springs 41 connected with the fixed frame of the machine and with the slideable upright members 36, normally tend to hold the members 36 in their upper position.

Slidably mounted between the uprights 12 at the opposite sides of the machine near the lower part of the machine, is a receptacle 42 for molten solder. Supported on the receptacle 42 are depending yokes 43, which support transversely arranged burner tubes 44 which may be connected in any suitable way with the source of fuel supply.

On the receptacle 42 is a toothed rack bar 45 which meshes with a pinion 46 on a transversely arranged, rotatably mounted shaft 47, on one end of which is a crank

handle 48 by which the receptacle 42 may be raised and lowered.

I will now describe the practical operation of my improved radiator repair machine, and the construction thereof will be made clearer in connection with such description.

It is a matter of general knowledge that it is the lower part of a radiator which ordinarily freezes up in cold weather, and which needs repair most frequently. The freezing ordinarily occurs in the tubes, and it is then necessary to repair and re-solder the breaks or splits in the tubes. Incidentally, I have here spoken particularly of freezing the lower portions of the tubes of the radiator, but it will, of course, be understood that my machine may be used for repairing injuries caused in a great variety of other ways.

For illustrating the operation of my machine more briefly, however, let it be assumed that some of the lower ends of parts of the tubes of a radiator have been frozen and bursted. These tubes are ordinarily extended through and connected with a cover plate for the water receptacle or tank, which in turn is soldered at its upper edges to the plate.

In the use of my machine, the burners 23 are lighted. The radiator is mounted on the support 15 with the fingers or lugs 18 projecting between the fins and the tubes, and the radiator is mounted in such position that when the support is swung over to substantially horizontal position, as illustrated in Figures 1, 2 and 4, the bottom of the radiator will project over the burner tubes so as to permit the melting of the solder around the upper end of the water tank. After this solder has been melted, the tank is removed, and the solder is melted around the plate at the lower ends of the tubes and around the fins.

In Figure 4 I have illustrated a portion of a radiator having the tubes 50 and the fins 51. The plate just mentioned, and the fins may be removed one at a time after the solder has been softened, by lowering the fingers 33 by means of the handle 34, until the fingers project, for instance, between the lowermost fin 51 and the next one above it, as illustrated in Figure 4. The operator may then put his foot upon the treadle 28 and press downwardly, whereupon the bell crank levers 26 will be manipulated for pushing the arms 30 forwardly, thereby forcing the fingers 33 against the endmost fin and forcing it off the tubes. The position of the parts at the finish of such operation is illustrated by dotted lines in Figure 4.

After the fins have been removed in the manner hereinbefore described, the tubes may be repaired in any suitable way, such, for instance, as described in my process Pat-

ent No. 1,319,670, issued October 21, 1919, and in my co-pending application for Patent, Serial Number 316,891, filed August 11, 1919.

5 After the tubes have been repaired, when it is desired to replace the fins the radiator is again placed on the support 15 and is swung to inverted vertical position, with the platform or support 15, in the position shown 10 in Figure 3, for instance, until the ends of the tubes at the bottom of the radiator stick straight upwardly in alignment with the holes 38. The relative positions of the parts are illustrated in Figure 5. One of the fins 15 is slipped into position with the holes therein exactly aligned with the ends of the tubes 50. It will be understood that the tubes fit very snugly in the holes in the fins. The operator then puts his foot on the treadle 40 20 and forces the frame 47 downwardly, whereupon the fin will be forced downwardly over the tubes, the ends of which will project through the openings 38 in the frame member 37, as illustrated in Figure 6. This operation can be repeated until all the fins have 25 been assembled on the radiator, and until the plate which forms the top of the lower tank is mounted on tubes in the radiator.

Either before or after the plate has been 30 placed in position, the platform or support 15 is moved to position until the bottom of the radiator stands immediately above the solder receptacle 42. Assuming that the solder in such receptacle has been melted by 35 heat from the burners 44, the operator then manipulates the crank 48 and raises the receptacle 42 until the lower end of the radiator is received therein for soldering the fins to the tubes. The solder will not stick to the 40 lower ends of the tubes, so there is no danger of stopping them up.

It will be seen that I have provided in my machine a very convenient, simple and inexpensive mechanism for removing the fins 45 from the tubes and for replacing them thereon.

The repairing of radiators is a somewhat delicate job, requiring care and ordinarily requiring considerable time. With my improved machine the time taken for repairing 50 a radiator in ordinary cases can be very greatly reduced.

Furthermore, I have found that by removing the fins by means of the machine including the fingers 33, much less injury is done to the fins than is the case where old methods are employed. The fins can be much more easily and quickly assembled on the tubes with my machine, and this operation 55 can be performed with less injury to the

parts than is ordinarily the case where the old methods are employed.

Some changes may be made in the details of the construction and arrangement of the parts of my improved radiator repair machine without departing from the real spirit and purpose of my invention, and it is my intention to cover by my claims any modified forms of structure or use of mechanical equivalents which may be reasonably included within their scope.

I claim as my invention:

1. In a radiator repair machine, the combination of a radiator supporting platform, means thereon to prevent longitudinal movement of the radiator, a heater arranged adjacent to the platform and in position to heat a portion of a radiator which is supported on said platform, and a radiator fin engaging arm movably supported above the heater, for the purposes stated.

2. In a radiator repair machine, the combination of a radiator platform, a series of upright fingers thereon designed to enter between the tubes and fins of the radiator to hold the radiator against longitudinal movement on the platform, a heater adjacent to and beneath one end of the said platform, a fin engaging device arranged above the heater, and means for operating it to remove the fin engaged thereby, from the tubes.

3. In a radiator repair machine, the combination of a tilting platform, fingers thereon designed to enter between the fins and tubes of a radiator to hold the radiator on the platform, a heater arranged adjacent to and below one end of the said platform when the platform is in a horizontal position, a fin removing device in position above the heater, a cross bar having openings therein to receive radiator tubes normally in position above the platform when it is in a vertical position, and means for moving said cross piece downwardly to press a fin on the tubes 100 extended through it.

4. In a device of the class described, the combination of a radiator platform, radiator supporting fingers mounted thereon and designed to enter between the fins and tubes 105 of the radiator to hold it on the platform when the platform is in a substantially vertical position, a solder tank, a heater mounted beneath it, and means for moving the solder tank upwardly to engage the lower 110 end of the radiator supported on the said platform.

Des Moines, Iowa, November 5, 1919.

CLYDE E. SCHULZ.
